COMBINED FOOD STORAGE TRAY AND
COVER THEREFOR

Robert H. MacKay, 1917 Cherry Blossom Lane,
Fort Wayne, Ind.

Filed Aug. 9, 1965, Ser. No. 86,492

Term of patent 14 years

(Cl. D44—10)

FIG. 1

FIG. 2

FIG. 3

FIG. 4

FIGURE 1 is a perspective view of a combined food storage tray and cover therefor showing my new design;

I claim:

The ornamental design for a combined food storage tray and cover therefor, as substantially shown.
